MATCH PACKAGE

Wendell D. Little, Indianapolis, Ind.

Application November 23, 1931
Serial No. 576,717

5 Claims. (Cl. 206—29)

My invention is concerned with packages of paper matches of the common type. Such packages comprise a block of paper matches enclosed within a strip of heavy paper or cardboard cover, 5 the untreated ends of the matches being secured between the back and the lower folded-over end of the cover. The other, or upper, end of the strip forming the cover acts as a flap which protects the matches and extends over the heads of 10 the matches and has its free end inserted beneath the lower end of the cover.

In the usual manner of using such matches, the package is grasped in one hand, and with the other hand the flap is lifted, a match is torn off, 15 and struck against the striking surface provided on the folded-over lower end of the cover. It is the object of my invention to produce a match package of the general type described which will be adapted for use with one hand.

20 In carrying out my invention I provide near the top of the flap which covers the matches a striking surface so positioned as to be engaged by the head of a match which has been bent forward from the block of matches and behind 25 which the flap has been inserted.

The accompanying drawing illustrates my invention: Fig. 1 is an isometric view of a package of paper matches embodying my invention; Fig. 2 is an end elevation of such a match package 30 with the flap closed and a match in position for striking; Fig. 3 is an end elevation of the match package showing the flap raised; and Fig. 4 is a front elevation of a match package illustrating a slightly modified construction.

35 In the match package of the type with which my invention is concerned, the uncoated ends of the matches 10 are received and held in place between the back 11 and the lower end 12 of a paper cover, the lower end 12 of the cover being 40 folded over the ends of the matches and the matches being held in place by a staple 13. From the upper end of the back 11, the cover of the package extends over the heads of the matches and downwardly, this end of the cover being cus- 45 tomarily adapted for insertion behind the end 12. The outer face of the lower end 12 of the cover is coated with some material which forms a striking surface for the matches.

In embodying my invention in such a match- 50 package, I provide near the top of the front face of the cover a transverse projection 15 which may be formed in any convenient manner. This projection has a lower surface that is preferably inclined upwardly and outwardly relatively to the 55 front face of the cover and is coated with mate-

rial on which a match may be struck. The position of the projection 15 is such that its coated lower surface will be engaged by the head of the match which has been bent forward from its usual place and lies in front of the cover, as illustrated in Fig. 1.

I find it desirable to provide on the cover below the projection 15 a transversely extending rib 16 upon which the match may bear as its upper end is drawn across the striking surface. This 60 rib 16 may be formed in any convenient manner, and conveniently is a narrow strip of wood glued to the outer surface of the cover.

In operation, the match package is grasped between the fingers and the palm of the user's hand, 70 and the flap is raised with the thumb. After the flap has been raised, the thumb is employed to bend one match forwardly when, with the assistance of the index finger, the flap may be lowered in rear of the forwardly bent match, as indicated 75 in Figs. 1 and 2. With the cover thus returned to its normal position, the match-head is forced transversely across the striking surface on the projection 16 with the thumb, and is thereby ignited.

In order to prevent deformation of the curved portion of the cover adjacent the upper ends of the matches due to its repeated flexing, I consider it desirable to provide the cover with a transverse score 18 at about the position illustrated in the drawing—i. e., approximately opposite the lower ends of the match-heads.

To facilitate the operation of bending a match forward after the flap has been raised, the rows of matches are preferably arranged as indicated 90 in Figs. 2 and 3, the lengths of the matches increasing from the back match-row to the front match-row. In Fig. 4 I have illustrated a match package in which the lower or striking surface on the projection 15 is transversely curved. By employing a projection of this shape, I am enabled 95 to obtain a more constant pressure between the match and its striking surface.

I claim as my invention:

1. A match package, comprising a plurality of 100 matches each having a stem of flexible material provided at one end with a head, a cover for said matches, said cover being formed of flexible material with its upper end folded over the headed ends of the matches and with the lower end of the cover folded over and secured to the opposite ends of the matches, and a projection extending transversely across the upper end of said cover on the exterior thereof, said projection having 105 a match-striking surface and being disposed so 110

that a match, while still secured to the lower end of said cover, may have its head brought into engagement with said striking surface and drawn therealong.

5. A match package as set forth in claim 1 with the addition that said cover is provided between its folded over ends and adjacent the match-heads with a transverse score-line to weaken the material of the cover and facilitate 10 movement of the upper end of the cover to expose the matches.

3. A match package, comprising a plurality of matches having stems of flexible tearable material, said stems being secured in said package 15 at their lower ends and having heads at their upper ends, a cover for said package, said cover being provided with a generally transversely extending projection having on its lower side a match-striking surface so disposed that a match, 20 while still having its lower end secured in said package, may have its head brought into engagement with said striking surface and drawn therealong.

4. A match package, comprising a plurality of 25 matches having stems of flexible tearable material, said stems being secured in said package

at their lower ends and having heads at their upper ends, a cover for said package, said cover being provided with a generally downwardly presented transversely extending striking surface projecting outwardly from that portion of the cover lying below it, said striking surface being disposed so that a match, while still having its lower end secured in said package, may have its head brought into engagement with said striking surface and drawn therealong.

5. A match package, comprising a plurality of matches each having a stem of flexible material provided at one end with a head, a cover for said matches, said cover being formed of flexible material with its upper end folded over the headed ends of the matches and with the lower end of the cover secured to the opposite ends of the matches, the upper end of said cover being provided exteriorly with a match-striking surface positioned so that a match, while still secured to the lower end of said cover, may have its head brought into engagement with said striking surface and drawn therealong, and an outwardly projecting rib extending transversely of the cover below said match-striking surface.
